(57) **CLAIM**

The ornamental design for a cartridge holder for anesthetic, as shown and described.

DESCRIPTION

FIG. 1 is a perspective view of a cartridge holder for anesthetic showing our new design;

FIG. 2 is a bottom plan view thereof;

FIG. 3 is a top plan view thereof;

FIG. 4 is a front elevational view thereof, the rear view being identical;

FIG. 5 is right side elevational view thereof, the left side being identical;

FIG. 6 is a perspective view of a second embodiment of the cartridge holder for anesthetic showing our new design;

FIG. 7 is a bottom plan view of the embodiment of FIG. 6;

FIG. 8 is a top plan view of the embodiment of FIG. 6;

FIG. 9 is front elevational view of the embodiment of FIG. 6, the rear elevational view being identical; and,

FIG. 10 is a right side elevational view of the embodiment of FIG. 6, the right side being identical.
